ENGINE CRANKCASE AND FILLER DEVICE

John C. Slonneger, Dallas, Tex., assignor to The Continental Supply Company, Dallas, Tex., a corporation of Delaware

Original application March 14, 1946, Serial No. 654,427. Divided and this application January 5, 1948, Serial No. 637

2 Claims. (Cl. 121--194)

1

This invention relates to new and useful improvements in breather systems for internal combustion engines.

One object of the invention is to provide an improved breather system particularly adapted to, but not limited to, one-cylinder internal combustion engines.

A particular object of the invention is to provide an improved system wherein the breather is open to the atmosphere only during the outer or bottom dead center portion of the crank shaft cycle and is closed to the atmosphere during the remainder of said cycle, whereby the loss of lubricating oil from the engine is substantially eliminated.

An important object of the invention is to provide an improved system wherein the lubricating oil entrained with the air escaping through the breather is trapped and permitted to drain or flow back into the crankcase and is thus conserved.

Another object of the invention is to provide an improved breather system which includes an enclosure having a vent to the atmosphere, an air passage to a crankcase and a movable member having means periodically opening and closing said passage, whereby an air stream may flow through said passage only during a minor portion of the cycle of revolution of the engine crankshaft.

Still another object of the invention is to provide an improved breather system which includes an enclosure having a vent to the atmosphere, and air passage to a crankcase, means in the enclosure for setting up whirling of the air therein whereby oil particles are separated from the air in said enclosure.

A further object of the invention is to provide a system wherein the breather is combined with the engine governor, whereby oil entrained in the air is separated from the latter and utilized to lubricate the governor, the surplus oil being drained or conducted back to the crankcase.

Another object is to provide in connection with the system, a filling device arranged so that additional oil may be introduced into the crankcase, while the engine is operating, without drawing sufficient air into said case through the device to disrupt the breather system.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a vertical section view through the top of the crank and governor of an internal combustion engine, illustrating a breather sys-

2

tem constructed in accordance with the invention.

Figs. 2, 3 and 4 are transverse sectional views taken on their respective lines of Fig. 1 and looking in the directions of their arrows, and

Fig. 5 is a vertical sectional view of the air-excluding oil filling device.

This application is filed as a division of my co-pending application filed March 14, 1946, Serial No. 654,427, now Patent No. 2,590,134.

In the drawings, the numeral 10 designates the top wall of an internal combustion-engine crankcase 11. The upper end of the camshaft 12 terminates just below the wall 10 and has a horizontally disposed gear 13 fastened thereon. This gear drives a pinion 14 secured on the lower reduced shank 15 of a tubular governor shaft 16. The governor shaft is supported in a horizontal ball bearing assembly 17 which is mounted in a collar 18. The collar fits snugly in a circular opening 19 and depends from a governor base 20 which is bolted on the wall 10.

The governor includes a dome-shaped housing 21 which is secured in a recess 22 by bolts 23. The base is flanged and has a vertical bore 24 which is a continuation of the bore of the collar 18. The upper end of the shaft 16 is shouldered and has the hub 25 of a grooved bracket 26, fastened thereon. The hub has a free rotating fit in the upper end of the bore 24. It is pointed out that oil accumulating in the bottom of the housing 21 may drain or flow into the bore 24 around the hub 25, thence down through said bore to the assembly 17 which will thus be lubricated. Since the lower end of the collar 18 is open to the crankcase, surplus oil may drain or flow into said case.

Angular governor arms 27 are mounted in the grooved bracket 26 on pins 28 and carry the usual weights 29 at the upper ends. These weights overhang fingers 30 extending inwardly in the grooved bracket and tend to swing the arms inwardly. A plunger 31 is mounted to slide vertically in the upper end of the shaft 16 and a disk head 32 which overhangs the fingers 30. The governor operates in the usual manner, whereby the weight arms are swung outwardly as the speed of rotation increases, which causes the fingers 30 to raise the plunger 31. A cup 33 is secured on top of the plunger head and receives a ball 34 on which the lower end of a detent 35 is spindled. The upper end of the detent is journaled in a socket 36 which is suitably mounted on the end of the arm 37 of a regulator, which will not be described since it is not a part of the invention.

A nipple 38 is secured in the top of the housing 21 and carries a vent cap 39 which opens the housing to the atmosphere and permits air to escape from the housing. The base 20 has a

port 40 which establishes communication between the interior of the housing and the top of a vertical chamber 41 formed at one side of the base. This chamber has an annular recess 42 at its lower end which receives the upper end of a flanged bushing 43, secured in an opening 44 in the crankcase wall 10. A nipple 45 has a sliding fit in the bushing and extends into the chamber.

The bottom of the nipple is flat so as to ride on the upper flat surface of the gear 13 and is provided with an annular flange 46 which prevents its from being forced upwardly through the bushing. The gear has diametrically opposite ports 47 located to register with the bore of the nipple 45 at each half rotation of the gear. An annular groove 48 is formed in the under side of the gear 13 and the ports 47 extend from this groove which is constantly open to the crankcase. From the foregoing, it will be seen that communication between the crankcase and the interior of the housing is set up by way of the groove 48, ports 47, nipple 45, chamber 41 and port 40 when the ports 47 are momentarily in registration with the bore of said nipple, and such communication is shut off when the ports are out of registration with the bore of the nipple.

It is pointed out that the camshaft 12 is timed to rotate once to every two revolutions of the crankshaft of the engine (not shown). The parts are so related and the ports 47 so positioned that each time the crankshaft reaches its outer or bottom dead center, one of the ports 47 of the gear 13 is in registration with bore of the nipple 45 and the crankcase is in communication with the atmosphere. The design and sizes of the elements are such, that each port 47 begins to open at approximately 15° before dead center and completes closing at approximately 15° after dead center. These figures are merely illustrative and the invention is not to be limited thereto.

The result of the foregoing arrangement is that during more than 300° of the revolution of the crankshaft, the crankcase is shut off from communication with the atmosphere, and that such communication is established for a period having a duration of less than 60° of said revolution. As pointed out, this period of communication occurs during the time the piston is at, or very near, its lowermost point within the cylinder, or the point commonly referred to as bottom dead center. By reason of the laws of harmonic motion, the actual longitudinal movement of the piston, as the crankshaft revolves from 15° or 20° in advance of bottom dead center to 15° or 20° following bottom dead center, is very slight so that compression of the gases within the crankcase during this period is negligible. Therefore, after the engine has been running a short period of time so as to become properly warmed, the gases within the crankcase reach a more or less static condition so far as expansion and contraction are concerned. During a major portion of the piston travel, the crankcase is shut off from communication with the atmosphere, and a partial vacuum exists therein. As the piston reaches a point very near to its lowermost point of travel, the breathing structure described commences to open. However, at this point, the pressure within the crankcase has very nearly returned to that of the atmosphere due to the compressive action of the piston. As the piston approaches and reaches bottom dead center, a very small amount of the gases within the crankcase may pass outwardly through one of the ports 47. Similarly,

as the piston passes bottom dead center and begins to move toward the head of the cylinder, a very small amount of air may be drawn into the crankcase before the port is closed. For all practical purposes, the flow of air or gases, in and out, during this period may be disregarded because the degree of piston travel is actually very slight, as previously pointed out. However, there is an additional factor which must be considered, and that is blow-by of the combustion gases from above the piston. No matter how well the engine is constructed, there will be a very slight amount of the combustion gases which will escape past the piston rings into the crankcase, and the major portion of the gases which flow through the ports 47 is constituted by such escaped combustion gases. Again, the quantity or volume of gas involved is very small so that only a low velocity is obtained as such gases pass upwardly through the bore of the nipple 45. The duration of the flow is relatively short since the ports are exposed for only a short period of time and also since only a very slight amount or volume of gas is present for disposal.

Thus, for more than 300° of the revolution of the crankshaft, there is a partial vacuum in the crankcase, whereby the pressure in the case is lower than atmospheric pressure. Conversely, during less than 60° of the revolution of the crankshaft, a pressure equal to or slightly greater than that of the atmosphere prevails in the crankcase. As pointed out, during this latter period of increased pressure in the crankcase, a small volume of air or gas is caused to flow from the crankcase through one of the ports 47. Such gas, in flowing from the crankcase, will carry a certain amount of mechanically entrained oil into the housing 21.

Owing to the larger area of the housing, the small volume air or air or gas undergoes expansion and the velocity of the stream is reduced. The centrifugal action set up by the governor arms 27 will whirl the air or gas, whereby the oil particles will be thrown outwardly and will accumulate on the cylindrical wall of the housing. Therefore, the oil is not only separated from the air, but it is trapped in the governor housing. Since the vent nipple 38 is comparatively small and since the ports 47 are closed during the major portion of the cycle of revolution of the crankshaft, ample time will be given to separate the oil from the air in said housing.

As hereinbefore pointed out the separated and trapped oil may drain into the bore 24 of the housing 28, lubricate the shaft 16 and bearing assembly 17 and return to the crankcase. A surplus of oil will flow down through the port 40 into the chamber 41, pass down around the nipple 45 and lubricate the surface of the gear 13 and the teeth of the pinion 14 before returning to the crankcase.

It is pointed out that the flow of oil downwardly from the governor housing into the crankcase is encouraged and facilitated by reason of the operation of this engine breathing device. The crankcase is under a partial vacuum for a major portion of each revolution of the crankshaft and carries a pressure equal to or slightly greater than atmospheric for only a short portion of each such revolution. Thus, during a major portion of the engine's running time, there will be a vacuum present within the crankcase tending to draw any displaced oil back into the case. The degree of vacuum obtained is sufficiently high to cause the oil to overcome capillary attraction or

surface tension and flow from between the surfaces of the various elements of the governor, such as the bushing 43 and the nipple 45. However, the pressure above atmospheric obtained during the minor portion of the cycle is not of sufficient magnitude or of sufficient duration to cause the oil to again flow upwardly into the governor structure. Thus, the breathing device becomes substantially unidirectional in so far as the return of oil to the crankcase is concerned. The forces tending to return the oil are of much longer duration and are greater than those forces tending to force the oil away from the crankcase. The net result is that oil passing into the governor housing along with the relatively small flow of air or gas thereinto, is ultimately all returned to the crankcase so that substantially no loss or dissipation through the breather cap 39 occurs.

An additional advantage of this predominance of a partial vacuum within the crankcase rather than a slight pressure above atmospheric is the prevention of escape of oil through the various joints and openings normally present in any crankcase. In this manner, the escape of oil past the oil seal rings around the crankshaft and other joints which may not be air tight, such as screw-threaded joints and the like, is prevented. In addition, the unidirectional action of this breather prevents power loss by eliminating the pumping of air in and out of the crankcase and furthermore avoids the contamination of the crankcase oil by foreign matter drawn in from the outside by said pumping of air in and out of the crankcase.

To implement further the desirable results obtained by this vacuum-maintaining breathing structure, a device is provided whereby oil may be added to the crankcase while the engine is operating without disrupting the breather system by the admission of additional air from the atmosphere. Such a device is shown in Fig. 5 and includes a collar 50 having its lower end internally and externally screw-threaded. The lower end of the collar is screwed into the top wall 10 of the crankcase at a convenient location.

The usual filler cap 51 is removably mounted on the upper end of said collar and an elongate nipple 52 has its upper end screw-threaded and screwed into the collar. A sleeve 53, larger than the nipple, telescopes said nipple and has its bottom closed and spaced from the bottom of the nipple. The upper end of the sleeve is spaced a short distance from the wall 10 and said sleeve is provided, at its top and bottom, with spacer lugs 54 which are welded or otherwise secured to the nipple to support the sleeve thereon.

The sleeve and nipple form a U-tube trap, whereby an oil column or seal is provided in the spaces within and between said nipple and sleeve. Added oil will unbalance this trap and overflow the upper end of the sleeve into the crankcase. Due to this oil seal free air is prevented from entering the case when oil is added. In order to prevent fluctuations in the oil seal column which may, due to the variable pressures in the crankcase, reach amplitudes sufficient to displace enough oil into the crank to break the seal, a small aperture 55 is made in the nipple 52 between the collar 50 and the upper end of the sleeve 53. When the cap 51 is in place, this aperture equalizes the pressure between the crankcase and the small body of air trapped in the nipple above the oil column therein, and,

since this trapped volume of air is small, the aperture may likewise be small and still effect the desired equalization of pressure. Without this vent, the resilience of the trapped body of air acts as a spring, which together with the mass of oil in the trap, forms an oscillating system having a natural frequency. When the frequency of the pressure changes within the crankcase approaches the natural frequency of the said air-oil oscillating system, the amplitude of oscillation may become great enough to throw some of the trapping oil into the crankcase. If this occurs, the oil seal will be affected because the height of the oil columns will be reduced, and when the cap 51 is consequently removed, the remaining oil in the trap may be sucked into the crankcase so as to defeat the oil seal by allowing air to enter. Since an engine may be operated at various speeds, it is very probable that at some speed the frequency of pressure changes within the crankcase will fall into synchronization as described. Therefore, the vent or aperture 55 is a very important feature and has much to do with the operation of this breathing system. At the same time, the oil seal described is also very important in permitting the addition of lubricating oil while preventing the entry of air at the same time.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In combination, an engine crankcase in which a variable pressure is exerted while the engine is running, and means for maintaining a substantial seal of the interior of said crankcase against outside atmosphere while oil is being introduced into the crankcase, said means comprising, an elongate imperforate open-ended filling tube extending through a wall of the crankcase and having a generally vertically disposed portion projecting a substantial distance into the interior of the crankcase, an elongate imperforate oil trap sleeve surrounding the vertical portion of the tube within the crankcase, the upper end of the sleeve being open and terminating in the interior of the crankcase, the lower end of the sleeve being closed, the open lower end of the tube being disposed a substantial distance below the open upper end of the sleeve, said sleeve containing oil at all times and forming with the tube a crankcase seal against the outside atmosphere, and the tube having a single small air vent in its wall within the crankcase and above the upper end of the sleeve.

2. The combination as set forth in claim 1, and a closure on the outer end of the filling tube.

JOHN C. SLONNEGER.
